[57] **CLAIM**

The ornamental design for fluorescent lamp, as shown and described.

DESCRIPTION

FIG. 1 is an elevational view of a fluorescent lamp, according to a first embodiment of the design;

FIG. 2 is a different elevational view of the first embodiment;

FIG. 3 is a top plan view of the first embodiment;

FIG. 4 is a bottom plan view of the first embodiment;

FIG. 5 is an elevational view of a second embodiment of the design;

FIG. 6 is a top plan view of the second embodiment;

FIG. 7 is a bottom plan view of the second embodiment;

FIG. 8 is an elevational view of a third embodiment of the design;

FIG. 9 is a top plan view of the third embodiment; and,

FIG. 10 is a bottom plan view of the third embodiment.
